UNITED STATES PATENT OFFICE.

OTTO WITTKOWSKI, OF DUSSELDORF, GERMANY.

AUTOMATIC STABILIZING APPARATUS FOR FLYING-MACHINES.

1,182,503.

Specification of Letters Patent.

Patented Mar. 16, 1915.

Application filed October 6, 1914. Serial No. 865,401.

To all whom it may concern:

Be it known that I, OTTO WITTKOWSKI, a citizen of the German Empire, resident of Dusseldorf, in the Province of the Rhine, Prussia, Germany, and whose post-office address is 19 Schwanenmarkt, Dusseldorf, Germany, have invented certain new and useful Improvements in Automatic Stabilizing Apparatus for Flying-Machines; and I do hereby declare the following to be a full, clear, and exact description of the invention, such as will enable others skilled in the art to which it appertains to make and use the same.

15 My invention relates to improvements in automatic stabilizing apparatus for flying machines, and more particularly in stabilizing apparatus of that class in which a pendulum is provided on the body of the flying machine by means of which stabilizing planes provided on the flying machine are set so as to return the flying machine to equilibrium whenever the equilibrium is disturbed.

20 The object of the improvements is to provide an apparatus of this class, which is not injuriously affected by the inertia of the pendulum when the flying machine changes its velocity.

25 With this and other objects in view my invention consists in the matters to be described hereinafter and particularly pointed out in the appended claims, reference being had to the accompanying drawings and to the letters of reference marked thereon.

30 In said drawings Figures 1 to 3, are diagrammatical side views of the flying machine equipped with my improved stabilizing apparatus and showing the flying machine respectively in normal or horizontal position, in the position in which the front end of the body has been thrown upward, and in the position in which the said front end is directed downward. Figs. 4 and 5, 35 are similar side views showing a modification of the invention, the flying machine being shown respectively in alighting position, and in the position when swimming on the water, Fig. 6, is a side view showing a detail of the machine shown in Figs. 4 and 5, and Fig. 7 is a detail view of a modified construction showing the hand-operated mechanism for setting the lifting plane.

35 Stabilizing apparatus of the class referred to above is objectionable in this respect, that the pendulum changes its posi-

tion by inertia when the flying machine suddenly changes its velocity. For example, when the front end of the body of the flying machine is thrown upward and the flying machine is retarded, the pendulum is advanced relatively to the body of the flying machine, and when the front end of the body is directed downward and the velocity is increased, the pendulum is rocked backward relatively to the body of the flying machine. These movements of the pendulum have the tendency to set the stabilizing planes in such a way, that the irregularity in the position of the flying machine is increased, instead of counteracting the same. Furthermore, when the flying machine is started from the ground or the surface of the water, and when it alights it is liable to be upset. In my improved flying machine these objections are avoided. For this purpose my invention consists in providing the pendulum for stabilizing the flying machine in longitudinal direction with a plane or planes which have a rocking support on a transverse axis and are so connected with the body of the flying machine that they are set, when the body is inclined at a certain angle, at a corresponding angle, in order that in each position of the body the forces acting on the same are at an equilibrium, which forces are the pull of the propeller and the resistance of the front faces of the body of the machine and the pendulum. This equilibrium follows the following equation:

$$j.m = k.n$$

(Figs. 1 and 3), the pull of the propeller acting on the center of gravitation of the masses of the flying machine. In addition to the planes means are provided whereby the said planes can be set manually, in order that when the flying machine is started from the ground or water or when it alights the supporting frame or float which provides the pendulum can be set with its front end directed upward, so that the flying machine is not overthrown when it alights or meets in its travel over the ground small resistances.

Referring at first to the example illustrated in Figs. 1 to 3, at the point *a* of the body of the flying machine a pendulum *c* is suspended, and on a transverse pivot *d* of the said pendulum a plane *e* has a rocking support, which plane provides a lifting

force. The said plane is connected with the body b of the flying machine by means of arms f and h and a link g , by means of which it is set according to the position of the body b of the flying machine relatively to the pendulum c . The resistance of the body of the flying machine acts along the line j , and the distance of the said line from the axis of the propeller i is m . The resistance of the plane e acts along the line k , which is at the distance n from the axis of the propeller. The pull of the propeller is represented by the arrow l . The connection of the pendulum with the plane o has been represented in a diagrammatical way by the members p . If the front end of the flying machine is thrown upward, and into the position shown in Fig. 2, for example by a current of air, the resistance j is increased, so that the velocity of the machine is reduced. By its inertia the pendulum has the tendency to move forward relatively to the flying machine and in the direction of the flight so as to assume the position c' shown in dotted lines. Thereby also the plane o would be moved upward and into the position shown in dotted lines. However, by the upward movement of the body of the flying machine the plane e is set in such a way that its front resistance is increased. Thereby the velocity of the pendulum is likewise retarded in the same way as that of the body b , so that the position of the pendulum is not changed.

In Fig. 3 I have shown the body of the flying machine in the position in which its front end has been thrown downward by a current of air r . Thereby the front resistance j is reduced and the velocity of the flight accelerated. The pendulum has the tendency to assume the position c'' which has been shown in Fig. 3 in dotted lines, and to turn the plane o into the position shown in dotted lines in Fig. 3, in which it would tend to direct the flying machine further downward. However, as the resistance is likewise reduced by setting the plane e , and the pull l of the propeller acts at a distance m from the point a from which the pendulum is suspended, the pendulum maintains its original position.

In Figs. 4 to 6 I have shown a flying machine in which the pendulum is provided by the frame work supporting the machine when moving over the ground or on the surface of the water, and in which in addition to the automatic setting means for the plane e' mounted on the pendulum, means are provided for setting the said frame work by hand.

Fig. 4 shows the flying machine when alighting or starting from the surface of the water, the floating body c' being in the position which is most favorable for starting or alighting. The body of the flying machine

is provided with wings or planes P . In order to impart to the float or frame c' the position shown in Fig. 4, the plane o' is set by hand by suitable mechanism in such a way, that the angle of inclination of the floating body C' to the body of the flying machine is changed, and thereby the plane e' is automatically set in such position that its front resistance has its smallest value. When the flying machine is flying the plane o' is again set in normal position.

In the modification shown in Fig. 7 the mechanism for setting the plane e' is constructed as follows: On the body of the flying machine having the wing P' , a sprocket wheel 2 is rigidly mounted coincident with the axis a'' from which the floating body C'' is suspended. The sprocket wheel 2 is connected through a chain 3 with a sprocket wheel 4 which is mounted on a slide block 5 guided in a slide way 6 which is secured to the floating body C'' . To the sprocket wheel 4 a plate 7 is secured which is formed with an eccentric cam slot 8. To the plane e' two arms 9 and 10 are secured which are connected by links 11 and 12 with a rocking lever 13 having its fulcrum fixed on the body C'' at 14. One end of the lever 13 is engaged by the cam slot 8. To the slide block 5 a rod 15 is jointed which is screw-threaded at its end and is engaged by a hand wheel 16 the hub of which is mounted for rotation in a bracket 17. When the sprocket wheel 4 and the cam plate 7 are rotated from the sprocket wheel 2, the cam slot 8 rocks the lever 13 so as to change the position of the plane e' through the intermediary of the links 11, 12 and the arms 10. By shifting the block 5 together with the cam plate 7 longitudinally of the guide way 6 by means of the hand wheel 16 and the rod 15 the lever 13 is likewise rocked. Both operations are independent of each other.

The pendulum or float framework c^3 is rigidly connected with bearings s , s of a worm t , and it has a rocking support on the body of the flying machine at a' . On the pivot a' a cam plate u is mounted which is adapted to be rocked by the worm t from the medial position w into the position x or y , Fig. 6, and the pendulum c^3 can rock independently of this movement with the cam plate u into the positions x or y . By the rocking movement of the cam plate u the point z of a lever B having a rocking support on the body of the flying machine at A is moved toward or away from the pivot a' and this movement is transmitted through members p' to the plane o' . The pressure of the plane o' on the cam plate u can not displace the latter because the cam plate is locked against such displacement by the worm t .

In the normal position shown in Fig. 5 the pressure of the body of the flying machine

passes through a point which is located before the center D of the pressure of the water acting on the float, and the center of gravitation of the float is located at the rear thereof. When starting the machine the plane e' is set by hand in horizontal position, so that the resistance in the direction of the flight and the lifting force E of the plane e' have their smallest value. After the flying machine has been started, the force exerted by the weight of the body of the machine and acting downward in the point a' is replaced by an upwardly acting force G caused by the lifting effect of the air on the wings of the machine, the center of gravitation C of the float being gradually shifted forward until it is below the pivot a', and the float has the position shown in Fig. 4. This inclined position of the float is further assisted by the driving force of the water propeller F which is driven from the motor of the flying machine. Therefore, when starting, the float will first rise with its front end from the water, and when alighting its rear end will first be immersed. Thereby the front end of the boat can not be immersed into the water, and the machine is not overthrown. When after starting, the driving apparatus or float has been released, the plane e' is brought into an inclined position corresponding to the equilibrium of the forces j, k, and l shown in Figs. 1 to 3. In order to deaden the shocks of the waves below the float, the water propeller F is disposed below the lowermost point of the float, so that the propeller is the last part of the system which leaves the water and the first one which is immersed into the water. It will readily be understood, that by setting the driving frame or float at an angle, less shock occurs when starting or alighting, because the frame can easily jump over uneven ground and the float can easily follow the movements of the waves, without transmitting the whole movement to the body of the flying machine.

I claim herein as my invention:

1. In a flying machine, the combination with the body, and a plane for steering the same vertically, of a pendulum on said body adapted to control said plane, and automatic means in movable relation with the pendulum for varying the air resistance of the pendulum according to the inclination of the body to the direction of the flight.
2. In a flying machine, the combination with the body, and a plane for steering the same vertically, of a pendulum on said body adapted to control said plane, a plane on said pendulum, and automatic means for

setting said plane on the pendulum at different angles to the direction of the flight according to the inclination of the body to the direction of flight.

3. In a flying machine, the combination with the body, and a plane for steering the same vertically, of a pendulum on said body adapted to control said plane, a plane on said pendulum, automatic means for setting said plane on the pendulum at different angles to the direction of the flight according to the inclination of the body to the direction of flight, and hand operated means to set said plane on the pendulum.

4. In a flying machine, the combination with the body, and the wings mounted thereon, of a driving frame adapted to float and rockingly connected with the body, the vertical line passing through the point of connection of the body and frame being located in front of the center of gravitation of the frame when the flying machine is floating on the water.

5. In a flying machine, the combination with the body, wings mounted thereon, and a steering plane for steering the body vertically, of a driving frame adapted to float and rockingly connected with the body and adapted to control said steering plane, the vertical line passing through the point of connection of the body with the driving frame being located in front of the center of gravitation of the frame when the flying machine is floating on the water, a plane on said driving frame, automatic means for setting the plane on the driving frame at different angles to the direction of the flight according to the inclination of the body to the direction of flight, and hand operated means to set said plane on the driving plane.

6. In a flying machine, the combination with the body, and the wings mounted thereon, of a driving frame adapted to float and rockingly connected with the body, the vertical line passing through the point of connection of the body and frame being located in front of the center of gravitation of the frame when the flying machine is floating on the water, and a propeller on said driving frame mounted below the lowermost part of the same.

In testimony whereof I have signed my name to this specification in the presence of two subscribing witnesses.
